UNITED STATES PATENT OFFICE.

HENRY G. SCHERER, OF CANTON, OHIO, ASSIGNOR TO THE MILLER PASTEURIZING MACHINE COMPANY, OF CANTON, OHIO, A CORPORATION OF NEW JERSEY.

REFRIGERATING APPARATUS.

948,101.

Specification of Letters Patent. Patented Feb. 1, 1910.

Application filed July 24, 1908. Serial No. 327,550.

To all whom it may concern:

Be it known that I, HENRY G. SCHERER, a citizen of the United States, residing at Canton, in the county of Stark and State of Ohio, have invented certain new and useful Improvements in Refrigerating Apparatus; and I do hereby declare that the following is a full, clear, and exact description of the same, reference being had to the accompanying drawing, making a part of this specification, and to the numerals of reference marked thereon, in which—

Figure 1, is a perspective view showing the apparatus and illustrating parts broken away. Fig. 2, is a vertical longitudinal section, except the pump is shown removed. Fig. 3, is an end view of the brine tank. Fig. 4, is a transverse section of the ice spraying pipe.

20 The present invention has relation to refrigerating apparatus and it consists in the novel construction hereinafter described and particularly pointed out in the claims.

Similar numerals of reference indicate 25 corresponding parts in all the figures of the drawing.

In the accompanying drawing, 1 represents the ice tank, or receptacle, which may be of the form shown, or it may be of any 30 other desired form. Below the tank 1, is located the brine receptacle 2, which may be of the form shown and is located directly below the ice tank 1, and is for the purpose of receiving and holding the brine which accumulates from the melting of the ice, and the returned brine after it has been forced 35 through refrigerating pipes or coils, which pipes or coils are of course to be located within and inclosed by the refrigerator, or 40 any structure within which freezing or refrigeration is required.

For the purpose of supporting the ice the rack bars 3 are provided, which rack bars constitute the bottom of the ice receptacle, 45 and of course support the ice contained in the receptacle. For the purpose of straining the liquid brine as it passes into the brine or liquid receptacle 2 the screen 4 is provided, which is supported in any convenient and well known manner and is located just below the rack 3. The liquid receptacle 2 is extended at one end some distance beyond the ice tank 1, for the purpose of providing a means for supporting the 50 suction pipe 5, and also supporting the

55 pump 6, to which pump the suction pipe 5 is connected in the ordinary manner. The pump herein illustrated is simply conventional as it forms no particular part of the present invention, except that a pump of some kind must be employed to withdraw the brine from the tank and to force the same through proper refrigerating pipes or devices or it is used for any purpose designed. 65

It will be understood, that the present invention can be and is, to be employed for various purposes, wherein refrigeration and freezing are required. From the pump 6 extends the pipe 7, which pipe leads to refrigerating coils 8, but I do not desire to be confined to the construction of refrigeration herein shown, as the illustration here employed is simply conventional, and is used only for the purpose of properly illustrating a complete and operative device or apparatus. From the refrigerating coils 8 leads the return pipe 9, which return pipe is properly connected to the perforated spray or sprinkling pipe 10, which spray or sprinkling pipe is properly connected to the upper part of the ice tank, being supported near its opposite ends by the front and rear walls 1^a, 1^b, respectively, thereof, and should be located about midway between the sides of 85 said tank. The spray pipe is closed at the end opposite to its intake end by a cap 10^a. The pipe 10 is provided with a series of apertures 11, which apertures are for the purpose of permitting the return brine to 90 fall by gravity upon the ice contained in the ice tank 1. Near the end of the liquid receptacle 2 from which the brine is pumped or forced are located the screens 12 and 13, which screens are for the purpose of removing any foreign substance, and of course 95 properly screening the brine after it has passed through the screen 4.

In the drawing I have illustrated two screens located adjacent each other, but I do not desire to be confined to the number of screens shown. For the purpose of providing a means for removing any sediment that may accumulate in the liquid receptacle 2, the removable end 14 is provided, which removable end is preferably held in position by means of the bar 15, which bar and end are held by means of the clips 16.

The operation of the present invention is substantially as follows, the necessary 110

amount of ice is placed in the tank 1 together with such other ingredients as may be required such as salt and a quantity of water poured upon the ice, or the ice permitted to melt until a quantity of liquid is contained in the liquid or brine receptacle 2, after which the pump 6 is set in motion and the brine forced through the necessary pipes to produce refrigeration and return 10 to the perforated pipe 10 where it is permitted to flow over and percolate through the ice thereby producing a continuous circulation of the brine.

Having fully described my invention what 16 I claim as new and desire to secure by Letters Patent, is—

1. In a refrigerating apparatus, the combination of an ice tank having a bottom composed of rack bars, a liquid receptacle, 20 the said ice tank mounted upon said liquid receptacle and a portion of said liquid receptacle extended beyond said ice tank, a horizontal screen interposed between said rack bars and said liquid receptacle, vertical screens located in said liquid receptacle between the portion of said receptacle immediately below said ice tank and the said extended portion, and a sprinkling pipe provided with a series of apertures located in 25 the upper part of said ice tank, substantially 30 as and for the purpose specified.

2. In a refrigerating apparatus, the combination of an ice tank having a bottom formed with openings therein, a liquid receptacle, the said ice tank being mounted 35 upon the said liquid receptacle and a portion of said liquid receptacle extending beyond one wall of said ice tank, a vertical screen located in said liquid receptacle between the portion thereof immediately below said ice 40 tank and the extended end of the liquid receptacle, and a spray pipe formed with a series of apertures located in the said ice tank.

3. A refrigerating apparatus having an 45 ice chamber comprising front, rear and side walls, a pipe extending through said chamber and supported at or near its opposite ends by the said front and rear walls, the said pipe being formed with a series of 50 apertures, and connections between one end of said pipe and a brine circulating means, the opposite end of the said pipe being closed by a cap.

In testimony that I claim the above, I 55 have hereunto subscribed my name in the presence of two witnesses.

HENRY G. SCHERER.
